UNITED STATES PATENT OFFICE.

FREDERIC H. ISAACS, OF NEWARK, NEW JERSEY.

DESIGN FOR A NECKTIE-SHIELD.

SPECIFICATION forming part of Design No. 28,794, dated June 7, 1898.

Application filed September 13, 1897. Serial No. 651,544. Term of patent 14 years.

To all whom it may concern:

Be it known that I, FREDERIC H. ISAACS, a citizen of the United States, residing at Newark, in the county of Essex and State of New Jersey, have invented and produced a new and original Design for Necktie-Shields, of which the following is a specification, reference being had to the accompanying drawings, showing the same in full.

My invention relates to the unitary design for a necktie-shield illustrated in the accompanying drawings, in which—

Figure 1 is a rear or inner side view of the shield. Fig. 2 is a top plan view of the same.

The leading or material features of the design appear in the following description.

A represents a bowed or curved shield-plate formed with a central notch or recess b, opening through its bottom edge, and with depending arms or projections c, disposed on opposite sides of said recess. Extending around this recess on the inner side of the

shield is a substantially horseshoe-shaped concavity d, and on the outer side a correspondingly-shaped boss or convex raised portion e. The shield-plate is provided adjacent to its upper edge with a series of apertures f, and each arm or projection c is provided with an aperture f'. The upper edge g of the shield-plate has a slight incurve throughout its length, while the lower edge h thereof is curved inwardly for a short distance from its ends and thence outwardly, as shown, to form the short depending arms or projections c.

Having thus described my invention, what I claim as new, and desire to secure by Letters Patent, is—

The design for a necktie-shield, substantially as herein shown and described.

FREDERIC H. ISAACS.
